(57) **CLAIM**

The ornamental design for a combined wick and wick holder, as shown and described.

DESCRIPTION

FIG. 1 is a perspective view of a combined wick and wick holder showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is another perspective view thereof, in a state of use with a combustion device.

The broken lines showing a combustion device in FIG. 8 depict environmental structure. All other broken lines depict portions of the combined wick and wick holder. The broken lines form no part of the claimed design.
